ADAM M. GIBSON, OF CHICAGO, ILLINOIS.

CARBURETER.

1,286,282.

Specification of Letters Patent.

Patented Dec. 3, 1918.

Application filed February 9, 1914. Serial No. 817,395.

To all whom it may concern:

Be it known that I, ADAM M. GIBSON, a citizen of the United States, residing at Chicago, in the county of Cook and State of Illinois, have invented certain new and useful Improvements in Carbureters, of which the following is a specification.

My invention relates to carbureters for internal combustion engines, and has for its 10 principal object to provide a carbureter which, for the several reasons to be herein-after made apparent, will operate more effectively, economically and in general more satisfactorily than the carbureting devices in 15 use at the present time.

A further object of the invention is to provide a carbureter which will be compact, light, inexpensive to manufacture and of such simple and strong construction as to be 20 durable and not likely to get out of order.

The carbureter of my invention is intended particularly for gasoline engines employed for driving automobiles, but might be used to advantage in other situations.

According to the common practice, the 25 volume of the mixture of gasoline and air introduced into the cylinders of an explosive engine is regulated by means of a throttle valve arranged in the pipe connecting the carbureter with the manifold of the engine. As a result when the throttle valve is partially closed the body of air and fuel has the greatest velocity at the throttle valve due to the constriction of the conduit at this

30 point. My invention proceeds upon the theory that the air should have its greatest velocity, at low speeds as well as high speeds, through the carburation chamber, that is, at the place where the air acts upon the gasoline

35 or other fluid hydrocarbon employed as fuel, and draws the same into the engine. The invention, therefore, contemplates eliminating the ordinary throttle valve usually interposed between the engine and carbure-

40 ter and providing a carbureter having valves therein which are directly controllable by the person who operates the engine to vary the volumes of air and fuel in accordance with the desired speed. In other

45 words the constriction of the conduit through the fuel supply system takes place at the point of mixture of air and fuel with

the result that the air and fuel are thoroughly mixed in proper proportions and the mixture supplied to the engine in the proper 55 quantities dependent upon the speed of the engine and consequent intensity of vacuum in the cylinders. For a low speed the fuel port of the carbureter is constricted but this is accomplished by a similar constriction of 60 the air port so that the velocity of air past the fuel port is not affected. In the ordinary system the constriction of the supply pipe at the throttle valve makes the flow of air past the gasoline nozzle very sluggish so that at 65 low speed the fuel is incompletely mixed with the air and not completely drawn into the engine cylinder. To counteract defective vaporization and inspiration it is customary to increase the volume of the fuel drawn 70 from the gasoline nozzle by opening the gasoline duct wider than would be necessary if all of the fuel in the carburation chamber could be properly vaporized and drawn into the cylinder. As such adjustment of the 75 needle valve gives too rich a mixture at high speed, carbureters are ordinarily provided with suction-operated secondary air valves which supply additional air to the mixture with a certain intensity of vacuum in the 80 cylinders. The expedient of introducing air into the system between the carbureter and the engine will, of course, decrease the velocity of the primary air passing the gasoline nozzle thereby diminishing its effectiveness 85 in vaporizing the fuel and producing a homogeneous mixture of fuel and air. In accordance with my invention all of the air is introduced into the system at one point and in such manner as to pass adjacent to 90 the gasoline nozzle. Therefore at all speeds the velocity of air around the gasoline nozzle is considerable. The volume only is varied in accordance with the volume of the fuel supply.

95 The invention provides further for an adjustment as between the air and fuel valves to permit the proportions as between the fuel and air to be varied.

In its preferred form the invention provides for seating the gasoline valve so that the usual float controlled mechanism governing the flow of gasoline to the nozzle may be dispensed with and also the cut-off

valve in the gasoline supply pipe. However, a float operated valve may be used in my system if desired.

Another feature of the invention is that it provides a simple arrangement for increasing, at the will of the operator, the amount of fuel introduced into the charges, for example, when additional power is required as in hill climbing. Preferably the air and gasoline valves are controlled by the quadrant lever and connecting mechanism used ordinarily for operating the throttle valve. In the preferred form of my invention a movement of the quadrant lever through a certain arc increases the supply of air and gasoline proportionately. A further movement results in an added increment of fuel. These arrangements result in a very considerable economy of fuel particularly when the full power of the engine is not required, for reasons that will be made apparent hereafter.

The invention consists further in an arrangement whereby the controlling member or arm of the carburetor may be moved in either one direction or the other to produce the same movement of the valves so that the carburetor may be placed upon either the right hand or left hand side of the car, as may be expedient.

The invention consists in such other new and improved constructions, arrangements and devices relating to carburetors and fuel supply controlling apparatus for internal combustion engines as will be hereinafter described and claimed.

The invention is illustrated, in certain preferred embodiments, in the accompanying drawings wherein—

40 Figure 1 is a sectional view of one form of the invention;

Fig. 2, a view, in perspective, of the air valve;

Fig. 3, a view similar to Fig. 1 illustrating another form;

Fig. 4, a view, in perspective of the air valve employed in this type.

Fig. 5, a fragmentary view, in elevation, of the device shown in Fig. 3;

50 Fig. 6, a longitudinal sectional view of another form of carburetor more completely embodying all of the improvements constituting the invention;

Fig. 7, a plan view of the same, and

55 Fig. 8, a view similar to Fig. 6 but showing the parts in different relative positions.

Like characters of reference designate like parts in the several figures of the drawings.

Referring first to Figs. 1 and 2, 10 designates a casing closed at the top by a bonnet 11 and with its lower end open. 12 designates a gasoline nozzle supported in the lower end of the casing 10 by the integrally formed cross web 13. 14 designates the gas-

oline supply pipe which is tapped into the nozzle 12. The casing is formed with a nipple 15 for the pipe which conducts the mixture to the engine manifold. Within the casing 10 is an air valve 16 of the piston type having a hollow spindle 17 projecting through the bonnet 11 to the upper end of which is attached an operating arm 18 preferably provided with a spring click 19 which operates against the notched perimeter 20 of the bonnet 11 and the flange 21 to which the bonnet is secured. Within the bore, extending through valve 16 and its spindle 17, is arranged the stem 22 of a needle valve 23, the upper end of the stem being threaded, as indicated at 24, and engaging a corresponding interior thread on the spindle 17. By this arrangement the position of the needle valve may be adjusted with respect to the air valve 16. The latter is formed with ports 25 and on its under side has a conical face 26 adapted to fit a conical seat 27 formed on the gasoline nozzle 12. A spring 28 is interposed between the air valve and the bonnet 11. The lower edge of the air valve 16 is formed to provide reversed helical cams 29 which bear against the portions of the web 13 on opposite sides of the nozzle 12. When the valve 16 is rotated by turning or operating rod 18, the air valve is raised so as to allow air to flow past the gasoline nozzle 12 and into the ports 25. As the valve is raised the space between the seats 26, 27 is increased so as to increase the flow of air through the system.

As valve 16 rises it carries with it the needle valve 23 opening the duct in the gasoline nozzle. The needle valve is tapered or otherwise formed so that in successive positions of the valve (up to a certain distance of the valve from its closing position) the increased flow of gasoline will be approximately proportional to the increase of air. For any given degree of vacuum in the engine the volume of air passing through the carburetor is dependent upon the aggregate cross sectional area of ports 25, supposing this area to be not in excess of the cross sectional area of the nipple 15, and of the pipes connected therewith. Preferably the carburetor is designed so that the effective size of the space between seats 26 and 27, that is, the capacity of this space for passing air, exceeds the aggregate capacity of the ports 25 before the valve 16 reaches its uppermost position. A further upward movement of the valve increases the effective size of the gasoline port and therefore increases the outflow of gasoline but there will be no proportionate increase of air as the maximum flow of air, for the assumed vacuum, has already been reached. The result is that the mixture is enriched. For the normal operation the proportion between air and fuel may

be varied by adjustment of the stem 22 of the needle valve. The operating arm 18 may be provided with any suitable connections for moving the same. For example, if the carbureter is used on an automobile, the arm 18 may be connected with the quadrant lever on the steering wheel.

Another form of carbureter constructed in accordance with the same principles is shown in Figs. 3 to 5 inclusive. The casing 30 is provided with an internal annular web 31 on the under side of which is formed a conical seat 32 for an air valve 33. This valve is formed with a yoke-like spindle 34 which slides and revolves in the web 31 and supports, with a threaded engagement, the stem 35 of a tapered valve 36 which has a taper generally the reverse of a needle valve 23. The stem 35 projects through the upper wall 20 of the casing 30 for convenience in adjusting the valve. The valve projects into the port 37 of a gasoline nozzle 38 supported on a plug 39 screwed into the lower end of the casing 30 and formed with air ports 40. The air valve 33 is formed with a cylindrical extension 41 to which is secured an operating arm 42 projecting through a helical cam slot 43 in the casing. The valve 33 is lowered in order to open it and carries with it the fuel valve 36.

A carbureter best embodying all of the improvements constituting my invention, as I now view the matter, is shown in Figs. 6 to 8 inclusive. 44 designates a casing closed at the top by a bonnet 45 provided with a nipple 46 for the pipe leading to the manifold and formed at the bottom with a plurality of radially arranged air ports 47. The gasoline nozzle 48 projects into the casing 44 from the bottom in the form of a screw plug. The gasoline supply pipe 49 is tapped into this plug. A portion of the interior surface of the casing 44 is conical, providing a seat 50 for the conical air valve 51, the latter being preferably notched or grooved as shown at 52, for the purpose of promoting the vaporization of the gasoline which passes the valve. The valve 51 is formed with a cylindrical extension 53 surrounding a web 54 depending from the bonnet 45. The needle valve 55 is supported by a stem 56 having a threaded engagement, for adjustment, with a spindle 57 revolvably mounted in and projecting through the valve 51 and the bonnet 45. The upper end of the spindle is provided with an operating member 58 on which is a clip 59 engaging a milled button 60 on the stem 56. The spindle 57 is formed with an integral collar 61 to which is secured a pin 62 carrying an anti-friction roller 63 which operates in a cam slot 64. The head 65 of the pin 62 projects through an elongated slot 66 in the cylindrical extension 53 of the valve 51. A

spring 67 is interposed between the valve 51 and the collar 61. Preferably the gasoline nozzle 48 is formed with a conical seat 68 and the needle valve has a similarly formed portion 69.

With the arrangement above described the needle valve can be made to seat and close the gasoline nozzle and at the same time any adjustment may be made, as between the needle valve and air valve which may be found necessary in order to obtain the correct proportion of gasoline and air in the mixture. If this necessitates the seating of the needle valve before the air valve seats this is possible through the yielding relation between the air valve and the spindle 57 in which the needle valve is mounted.

Preferably the slot 64 is formed to provide two oppositely slanted cams each having an amplitude of a quarter circumference. The roller 63 operates in one of these cams with the carbureter arranged at one side of the machine. The carbureter can be placed at the other side of the machine by turning the spindle 57 so that the roller will operate in the other cam.

In Fig. 7 the full line representation of the operating arm 58 shows the arm at the lower end of one of the cams, the air and gasoline valves being closed in this position 95 of the arm. The dotted lines, designated 58', indicate the position of the operating arm at the high point of the cam with the valves wide open. The dotted lines, designated 58'', show the position which the arm 100 will assume when the valves are operated by the other cam.

Preferably the air valve 51 and its seat 50 are so designed that the space between them will pass, for a given vacuum in the engine, the maximum amount of air permitted by the cross sectional areas of the conduit through the rest of the system before the valve reaches its uppermost position. A further upward movement of the 110 valve opens the gasoline port wider and thereby admits more gasoline to the carburation chamber in proportion to the air supply which has now reached its maximum. Preferably but not necessarily, the 115 air valve is formed with a plurality of small by-passes 70 for the purpose of preventing or minimizing the dead space directly under the center portion of the valve.

Operation: With the operating arms 18, 120 42 or 58, as the case may be, connected with the quadrant lever on the steering post (by connections similar to those used for operating the familiar throttle valve), a movement of the quadrant lever will open the air 125 port or ports through the carbureter and at the same time open the port in the gasoline nozzle. The proper proportion between air

and fuel may be obtained by a proper adjustment of the needle valve the spindle of which, in each case, projects out of the carbureter casing so as to be capable of convenient manipulation. The speed of the engine is controlled by varying the volume of mixture. This control is effected in the carbureter itself instead of in the pipe between the carbureter and the manifold, so that all 10 of the air entering the system passes through the carburation chamber and its volume is directly governed with respect to the speed required of the engine. At high speed the air port is open wider and the 15 gasoline port as well. Since all of the air entering the system has to pass through the carburation chamber instead of being admitted in part through a secondary valve, as is the common practice, the velocity of the 20 air adjacent the gasoline nozzle is very great with the result that the gasoline is thoroughly broken up and vaporized and homogeneously mixed with the air. At low speed the same, or approximately the same, 25 velocity is maintained despite the weakened suction by the constriction of the air port which takes place simultaneously with and in proportion to the constriction of the gasoline port.

30 A constant proportion between air and fuel is maintained through a predetermined portion of the rotary and vertical movement of the piston, that is, through a certain angular movement of the quadrant lever. A 35 further movement of the lever involving a further rotary and vertical movement of the spindle and its valves increases the proportion of fuel to air. These arrangements make it possible to adjust and operate the 40 carbureter so as to make an economy in fuel, particularly when running the engine at less than full power, which is not possible, so far as I am aware, with any other carbureter. An explosive engine, when furnished with 45 a carbureter of any of the ordinary types, is very wasteful of the fuel when developing anything less than its maximum power. The carbureter is set or adjusted with a view to obtaining a mixture rich enough for the 50 maximum requirement of the engine. This means that under ordinary circumstances, that is, when the vehicle is running on good roads and carrying a medium load (supposing the engine to be used on an automobile) 55 the mixture is richer than it need be. My carbureter is capable of being adjusted so that in the ordinary operation of the engine the mixture will be relatively thin—that is, contain a small amount of fuel in 60 proportion to air. At the same time, by means under the control of the driver the proportion of gasoline to air may be increased whenever more power is required. For example, the fuel valve may be adjusted 65 with respect to the air valve so that during the first part of the opening movement of the valves the amount of gasoline admitted in proportion to the amount of air will be comparatively small. The exact proportion will be determined in any given case according to the usual and ordinary power required from the engine. Just enough gasoline will be admitted to give the power required and no more. The speed of the engine can, of course, be varied by opening and closing the valves more or less. The power developed under these conditions will be as great as it is possible to get from the amount of fuel used because while the amount of gasoline is small the volume of 80 the charge is not diminished since the amount of air is increased in proportion so that high compression in the cylinders is maintained. The mixture being thinner, it burns more rapidly and more completely. 85 Now, if more power is required the operator has only to raise the valves to a point beyond that at which the air orifice to the engine has reached its maximum and as a result of the increased effective size of the fuel orifice the mixture is enriched by an increment of fuel. This gives the engine greater power using more fuel in just such quantities as may be necessary.

The carbureter operates very advantageously in starting. To start the engine the operator opens the valves to the full, by the manipulation of the quadrant lever causing a flooding of the air passages with gasoline. The valves are then throttled down 95 close and the constriction of the port gives the air passing in contact with the overflow of gasoline a very considerable velocity causing it to thoroughly vaporize the gasoline. It is difficult to start a gasoline engine in 100 which the control is by means of a throttle valve because when the engine is throttled down the maximum constriction is at the throttle valve and not at the carbureter. The difficulty is remedied only in part by 105 flooding the carbureter. Moreover, in my apparatus the carbureter can be flooded from the steering wheel which is a matter of convenience in many cases.

If the form of the invention exemplified in Figs. 6 to 8 inclusive, is employed, it will be possible to do away with the float controlled supply valve ordinarily used in connection with carbureters and with the shut-off cock in the gasoline supply pipe since 110 the needle valve 69 can be made to seat in the gasoline nozzle and close the same. This is made possible for all adjustments of the needle valve by the yielding relation 115 between the air valve and the needle valve.

By constructing the device with the double cam slot 64 as shown in this form of the invention, it may operate to open the valves 120

either by right hand movement or a left hand movement, as may be expedient.

While I have described my invention as embodied in certain preferred constructions, 5 I realize that further modifications might be made without departing from the principles of the invention. Therefore I do not wish to be understood as limiting the invention to the particular constructions, arrangements 10 and devices shown and described except so far as said devices, arrangements and constructions are specifically made limitations in certain of the claims herein.

I claim:

15 1. A carbureter for internal combustion engines comprising a carburation chamber having air and fuel ports leading thereinto, and means controllable at the will of the operator of the engine for varying the inflow 20 of air and fuel to said chamber, said means comprising mixture and fuel valves, an anti-clinal cam and mechanism engaging said cam for operating both valves.

2. A carbureter for internal combustion 25 engines comprising a carburation chamber having air and fuel ports leading thereinto, and means controllable at the will of the operator of the engine for varying in constant proportions, adjustable at will, the inflow of 30 air and fuel to said chamber, said means comprising mixture and fuel valves, an anti-clinal cam and mechanism engaging said cam for operating both valves.

3. A carbureter for internal combustion 35 engines comprising a carburation chamber having air and fuel ports leading thereinto, valves for controlling the proportions of air and fuel passing through said carburation chamber and cam actuated controlling means 40 comprising an anti-clinal cam for simultaneously operating said valves.

4. A carbureter for internal combustion 45 engines comprising a carburation chamber having air and fuel ports leading thereinto, valves for controlling the proportions of air and fuel passing through said carburation chamber, cam actuated controlling means comprising an anti-clinal cam for simultaneously operating said valves, and means 50 for adjusting said valves, one with respect to the other, so as to effect a change in proportions as between the fuel and air in the mixture.

5. A carbureter for internal combustion 55 engines comprising a carburation chamber having air and fuel ports leading thereinto, valves for controlling the proportions of air and fuel passing through said carburation chamber, and controlling means for simultaneously operating said valves, said valves being capable of a differential movement to 60 permit them both to seat for different relative adjustments thereof.

6. A carbureter for internal combustion

engines comprising a carburation chamber 65 having air and fuel ports leading thereinto, valves for regulating the proportions of air and fuel passing through said carburation chamber, and a revoluble element for operating said valves, the movements of which 70 through a given portion of its arc of revolution moves said valves to or from their seats according to the direction of said movements, the movements of which element through another portion of said arc operating 75 to move said valves in reverse direction.

7. A carbureter for internal combustion engines comprising a casing formed with an air port, a fuel nozzle extending into said casing adjacent said air port, a mixture valve 80 in the casing, a fuel valve carried by said mixture valve, and a cam operated mechanism comprising an anti-clinal cam for varying the position of said mixture valve, the fuel valve being adjustable with relation to 85 the fuel nozzle and the mixture valve.

8. A carbureter for internal combustion engines comprising a casing formed with an air port, a fuel nozzle extending into said casing adjacent said air port, a mixture valve 90 revolvably mounted in said casing and provided with an operating arm, a fuel valve carried by said mixture valve, and an anti-clinal cam to give said mixture valve a longitudinal movement when it is revolved; the 95 fuel valve being adjustable with relation to the fuel nozzle and the mixture valve.

9. A carbureter for internal combustion engines comprising a casing formed with an air port, a fuel nozzle extending into said 100 casing adjacent said air port, a valve revolvably mounted in said casing and provided with an operating arm, a fuel valve carried by said first mentioned valve, and a pair of oppositely slanted cams adapted to give said 105 first mentioned valve reverse longitudinal movements when the valve is revolved.

10. A carbureter for internal combustion engines comprising a casing formed with an air port, a fuel nozzle extending into said 110 casing adjacent said air port, a valve in the casing, a needle valve mounted with capacity for longitudinal adjustment in said first mentioned valve which extends into the fuel nozzle and is adapted to close the same, and controlling means for varying the position of said first mentioned valve, said valves having a yielding relation with respect to each other which permits the needle valve to seat at all relative adjustments of said 115 valves.

11. A carbureter for internal combustion engines comprising a casing having an air port and formed interiorly with a conical portion, a conical valve arranged in said 125 conical portion of the casing, a fuel nozzle extending into said casing, a needle valve which extends into said nozzle, a spindle

supporting said conical and needle valves and provided with means for revolving it, and an anti-clinal cam which operates to move said spindle longitudinally when the same is rotated.

12. A carbureter for internal combustion engines comprising a casing having an air port and formed interiorly with a conical portion, a conical valve arranged in said conical portion of the casing, a fuel nozzle extending into said casing, a hollow spindle on which the conical valve is supported, a needle valve provided with a stem which extends through and projects from the bore 15 of said spindle and has a threaded engagement therewith, and an anti-clinal cam which operates to move the spindle longitudinally when said spindle is revolved.

13. A carbureter for internal combustion engines comprising a casing having an air port and formed interiorly with a conical portion, a conical valve arranged in said conical portion of the casing, a fuel nozzle extending into said casing, a needle valve 25 which extends into said nozzle, a spindle in which said needle valve is mounted with capacity for longitudinal adjustment and which supports the conical valve so that the latter is capable of slight longitudinal movement with respect thereto, means for rotating said spindle, and an anti-clinal cam 30 which operates to move said spindle longitudinally when it is rotated.

14. A carbureter for internal combustion engines comprising a casing having an air port and formed interiorly with a conical portion, a conical valve arranged in said conical portion of the casing, a fuel nozzle extending into said casing, a needle valve 35 which extends into said nozzle, a spindle in which said needle valve is mounted with capacity for longitudinal adjustment and which supports the conical valve so that the 40

latter is capable of slight longitudinal movement with respect thereto, means for rotating said spindle, a cam which operates to move said spindle longitudinally when it is rotated, and a spring interposed between the said conical valve and the spindle.

15. A carbureter for internal combustion engines comprising a casing, a bonnet which closes one end of the casing and is provided with a cylindrical web formed with oppositely inclined connected cam slots, a fuel nozzle extending into the opposite end of said casing formed with a conical seat, a hollow spindle extending through said bonnet and provided with an operating arm, a tapered needle valve formed with a conical portion corresponding with the seat of the fuel nozzle, and provided with a stem which extends through and projects from said spindle and has a threaded engagement therewith, a guide pin on said spindle adapted to operate in said cam slot, a conical throttle valve in said casing, the casing being formed with a corresponding seat, said valve being provided with a cylindrical extension surrounding the cylindrical web on said bonnet and formed with an elongated slot to receive the end of said guide pin, and a spring interposed between said throttle valve and said spindle.

16. In a carbureter the combination of a casing, a spindle vertically movable in the casing, a valve surrounding the spindle and vertically movable with respect thereto, a fuel valve adjustably supported on the spindle for movement therewith, and a resilient element interposed between the spindle and said first mentioned valve.
